UNITED STATES PATENT OFFICE.

HARRY L. BELL AND CHARLES C. SWEITZER, OF MISHAWAKA, INDIANA.

APPARATUS FOR FORMING PIPE-CORES.

SPECIFICATION forming part of Letters Patent No. 746,779, dated December 15, 1903.

Application filed June 30, 1903. Serial No. 163,715. (No model.)

To all whom it may concern:

Be it known that we, HARRY L. BELL and CHARLES C. SWEITZER, both of Mishawaka, St. Joseph county, Indiana, have invented certain new and useful Improvements in Apparatus for Forming Pipe-Cores; and we hereby declare that the following is a full, clear, and exact description thereof, reference being had to the accompanying drawings, which form part of this specification.

This invention is an improved machine for making cores for use in casting hollow metallic bodies, such as pipes, columns, &c.; and the object of the present invention is to produce a machine which can be used to make cores of various shapes and sizes, with or without holes or passages for ventilating purposes or for reception of stiffening-rods, the holes extending throughout the length of the cores, if desired.

The invention, in brief, comprises a feed-hopper, below which is a removable cylinder-casting, to which is attached a removable core-former adapted to form a core of a certain form and dimension and which can be replaced by other core-formers to produce different sizes or forms of cores. In rear of the cylinder are a series of reciprocating pitmen, preferably operated by eccentrics on a common shaft, but set so that the pitmen will complete their strokes in succession rather than simultaneously, and to the inner ends of said pitmen are detachably secured changeable plungers, which are provided in sets of different sizes to suit the different sizes of cylinder-castings in which the plungers operate to compress the sand or core-forming material fed from the hopper. Each set of plungers together conform to the shape of the chamber in the cylinder in which they operate. Stationary or movable rods are attached to or arranged between the plungers parallel with the line of reciprocation thereof and project into the core-former beyond the inner limit of the stroke of the plungers, said rods forming the vent-openings in the core at desired points. Suitable means are provided for operating the moving parts, and cores of any given size and form in cross-section can be readily made on the machine with rapidity and any length desired, the product of the machine being a core of any desired cross-

section conformable to the interior cross-section of the core-former employed.

While a single plunger might be advantageously used in the machine, we prefer multiple plungers, for the reason that less power is required in tamping or packing the core material, since with three plungers, for example, the power required to tamp the material to a desired degree is lessened approximately one-third, and, moreover, a better effect is produced, as the feed of material can be uninterrupted, whereas with a single plunger the feed is necessarily stopped by the plunger filling the chamber when in its innermost position, while with plural plungers when one is at its inner limit of movement the others are more or less retracted.

The several novel features and combinations constituting the present invention and for which protection is desired are summarized in the claims following the description of the machine illustrated in the accompanying drawings, which shows a practical embodiment of our invention in the best form now known to us and which we will now describe in detail.

In said drawings, Figure 1 is a side elevation of the complete machine. Fig. 2 is a longitudinal central vertical section therethrough. Fig. 3 is a top plan view. Fig. 4 is a detail front elevation. Fig. 5 is a front view of one cylinder-casting detached. Fig. 6 is a detail rear view of the plungers, showing their connections to the pitmen. Fig. 7 is a detail front view of a smaller cylinder-casting. Fig. 8 is a detail side view of a smaller plunger adapted to operate in the cylinder shown in Fig. 7. Fig. 9 is a detail view of a core produced by the machine shown in Figs. 1 to 4.

The hopper A is supported on standards B B, attached to the base-plate C, near one end thereof, said standards having bearings 95 c⁶ on their upper ends for the shaft b, which carries agitators B' within the hopper, adapted to feed down the material therein. The shaft b has a sprocket b' on one end, driven by a chain b² from a sprocket b³ on the main shaft D, which is journaled in standards C', rising from base C at the end opposite standards B.

Between the standards B, the bottom of

hopper A, and base C is placed a cylinder, consisting of a casting having a through passage or chamber E, whose internal diameter and configuration conforms to the external 5 diameter and configuration in cross-section of the core to be formed. In the top of the casting and communicating with chamber E is a feed-opening E', which communicates with the outlet of the hopper A and receives 10 the material fed therefrom. On the top and front side of said casting is a short transverse flange E², which fits into a corresponding recess A² in the lower front side of the hopper. In the base of said casting is a longitudinal 15 slot E³, which fits over a longitudinally-disposed rib C³ on the base C. Also in the base of the casting is a transverse slot E⁴, which when the casting is in position beneath the hopper coincides with a notch C⁴ in rib C³, 20 and a locking-bar C⁵ can then be slipped into and through slot E⁴ and notch C⁴, locking the cylinder securely in position, as is evident from the drawings. The standards B have 25 apertures B⁵ in their bases to accommodate the bar C⁵ and assist in retaining it in position. In the front end of the cylinder, concentric with chamber E, is an annular shoulder or recess e, adapted to receive an annular flange f on a collar F, attached to the inner 30 end of the former F'. This collar has diametrically opposite lugs f' projecting radially therefrom and adapted to be engaged by retainers e', attached to swinging arms e², hinged to the opposite sides of the cylinder- 35 casting, as shown at e³. After the flange f is fitted into recess e and lugs f' engaged by retainers e' the tube F' is firmly held in axial alignment with and forms a continuation of chamber E. Said tube F' corresponds in internal 40 diameter, size, and contour with the external form of the core to be made, tube F' practically forming a long core former or shaper.

From what has been stated it will be obvious 45 that the cylinder and core-formers are removable from the machine, and in practice we propose to provide each machine with a set of core-formers corresponding to the various sizes and shapes of cores which it is proposed to manufacture.

Suitable means for packing the material into the core-formers as it is fed from the hopper is provided, and we preferably employ the following-described mechanism for packing 55 the material into the core-formers. Intermediate the standards B and C' are two standards c, which stand transversely of the base and are provided in their upper ends with apertures or bearings c' for a plurality of reciprocal pitmen G, of which three are shown, arranged parallel and extending longitudinally of the base and in alignment with the chamber E and tube F'. The pitmen G are respectively connected at their rear ends 60 to eccentric-straps d', engaged with eccentrics d, fast to shaft D, said eccentrics being preferably set at different degrees on the

shaft, so that when the latter is rotated the several pitmen will be reciprocated together, but in successive order. Secured to the inner end of each shaft G is a plunger g, and in a machine having three shafts, as shown, we preferably make each plunger in the form of a third segment of a cylinder, so that when arranged in alignment and juxtaposition on the ends of shafts G the plungers together form a cylinder corresponding in exterior size and shape to the internal size and form of the chamber E in the cylinder, which the three plungers together fit and fill as one plunger 75 would do. In order to accommodate the machine to different sizes of cylinders, plungers must be provided of different sizes and changeable with the cylinders, so when a cylinder is changed properly-sized plungers may 80 be placed in the machine to coat therewith. The plungers are therefore preferably made detachable from the pitmen, and, as shown, are provided with sockets g' in their rear ends to receive the forward ends of the pitmen and 85 are locked to the pitmen by pivoted catches g², which engage slots or notches G' in the pitmen, as indicated in the drawings. Any other desired means for detachably connecting the plungers to the pitmen may be employed. We do not restrict ourselves to the 90 employment of three plungers. Two or more than three may be used. The shaft D is provided with a pulley D', by which it may be driven by belting from any suitable prime 95 mover or transmission device.

To form vents or openings in the cores, one or more rods may be employed extending into the chamber E parallel with the plungers. These rods may be stationary and affixed to 105 part of the machine in rear of the plungers, which are suitably chambered or grooved to allow them to reciprocate by or on the rods, or the rods may be attached to the plungers, projecting therefrom into the chamber E. An 110 example of a fixed vent-forming rod is shown at H in the drawings, said rod being arranged in the axial line of the core, and an example of a movable vent-forming rod is shown at h, the rod h being fixed to and projecting from 115 the inner end of one of the plungers g.

The foregoing description will impart a sufficiently clear and comprehensive idea of the invention, which, we repeat, is not limited to the specific forms or constructions of parts 120 shown. Changes therein within the scope of our invention can be readily suggested by an experienced mechanician.

One essential feature of the invention is removable interchangeable core-formers, another a plurality of plungers working in the cylinders, and another the combination of these two principal features in one machine.

In the machine shown the operation is briefly as follows: A cylinder of the desired 125 size is secured in place beneath the hopper, then the proper core-former tube is attached thereto, the proper relative plungers are next placed on pitmen G, and the hopper supplied 130

- with core-forming material. Power being applied to shaft D, the plungers are reciprocated, and the material fed into the cylinder is pushed outward and packed in the former 5 E by the plungers, which act successively upon different portions of the material in the chamber E. (If desired, a filler-plug may be placed in the former-tube F' or chamber E at the beginning of the operation to facilitate 10 the formation of the core and proper compactness thereof.) As the core increases in length it is gradually projected from the tube F' and may be ejected therefrom in any desired length upon a suitable receiver or carrier. (Not shown.) The core S may be cut 15 into lengths desired before drying and then baked. When the rod H is used, a central hole or vent-opening s will be formed in the core, and by using rods h on the several plungers other holes s' will be formed in the core. These holes extend longitudinally thereof 20 and may be used for venting purposes to facilitate the drying of the core, or rods or bars can be slipped in the holes to stiffen it, as is desirable in long cores. When another 25 size of core is to be made, the machine is stopped, the core-former removed and replaced by a core-former of the desired size, and the core-making operation repeated, as 30 described.
- The size of the cores that may be produced with this machine with any one of the cylinders is only limited by the strength or capacity of the plungers. For example, in the three 35 cylinders illustrated by the drawings forty-two different sizes of cores of all shapes can be produced. A core may be made with a core-former smaller than the chamber in the cylinder, or we may make a core larger than the 40 chamber in the cylinder, and that this "core-former," as we term it, is detachable and may be made of any shape or size. A number of different sizes of cores can be made with our cylinder, only the core-former should not 45 be so large that it exceeds the capacity of the cylinder or so small that the plunger cannot effectually work the material out of the cylinder. The casting directly under the hopper and the plungers does not have to be removed, except when making cores too large 50 or too small for the effective use of that particular cylinder.
- Having thus described our invention, what we therefore claim as new, and desire to secure by Letters Patent thereon, is—
1. In a core-forming machine, a chamber, means for feeding material thereto, a plurality of segmental plungers operating in said chamber, and together conforming to the contour thereof, a driven shaft, a series of eccentrics thereon, eccentric-straps and pitmen connecting the eccentric-straps to the plungers, said eccentrics being arranged to operate the plungers in succession.
  2. In a core-forming machine, a changeable chamber, means for feeding core-forming material thereto, a plurality of changeable plungers all working within and together conforming to the contour of the chamber, means for operating the plungers in succession, and a changeable core-former attached to said chamber, and adapted to shape the core, substantially as described.
  3. In a core-forming machine, a hopper, and a changeable chamber; with reciprocating pitmen, and changeable plungers attached to said pitmen and together operating in said chamber, substantially as described.
  4. In combination, a hopper, a changeable cylinder, a changeable core-former attached to said cylinder, a changeable plunger operating in said cylinder, and means for operating said plunger.
  5. In a core-forming machine, a hopper, a chamber thereunder, a tubular core-former attached to said chamber, a series of reciprocating pitmen in rear of said chamber, and segmental plungers attached to said pitmen and all operating within said chamber in succession, for the purpose and substantially as described.
  6. In combination, a hopper, a changeable chamber thereunder, a changeable core-tube attached to said chamber, a series of reciprocating pitmen in rear of said chamber, and changeable plungers attached to said pitmen and all operating in said chamber, for the purpose and substantially as described.
  7. In combination, a cylindrical chamber, a plurality of segmental-shaped plungers operating in said chamber and together conforming to the contour thereof; vent-forming devices in said chamber, and means for operating the plungers in succession, substantially as described.
  8. In a core-forming machine, a hopper, a casting below the hopper having a horizontal chamber, a feed-opening communicating with the hopper, and setting and locking slots in its base; with means for locking the casting in position.
  9. In combination, a hopper, a removable casting thereunder, having a chamber, a rib on top engaging a recess in the base of the hopper, a feed-inlet communicating with the hopper, and longitudinal and transverse slots in its base, with a centering-rib and locking-bar respectively engaging said slots to retain the casting in place.
  10. In combination, a hopper, a removable casting thereunder having a chamber, a rib on top engaging a recess in the base of the hopper, a feed-inlet communicating with the hopper, and longitudinal and transverse slots in its base; with a centering-rib and locking-bar respectively engaging said slots to retain the casting in place, a series of reciprocating pitmen, plungers on the ends of said pitmen operating in said chamber and together conforming to the contour thereof; and means for operating said plungers, substantially as described.
  11. In a core-forming machine, the combination of a removable casting having a cham-

ber, and a feed-inlet above said chamber, and swinging, locking-arms on the sides of the casting with a core-former detachably fitted to the outer end of said chamber; having lugs 5 to engage the locking-arms for fastening the core-former to said casting, a feed-hopper above the chamber; and means for packing the material in said chamber.

12. In a core-forming machine, the combination of the hopper, a removable casting below the hopper having a horizontal chamber, a feed-opening in its top communicating with the hopper, and setting and locking slots in its base; with means for locking the casting 15 in position, a series of plungers operating in said chamber; and means for operating said plungers in succession.

13. In combination, a hopper, a removable casting thereunder having a chamber, a feed-inlet communicating with the hopper, and longitudinal and transverse slots in its base; with a centering-rib and locking-bar engaging 20 said slots to retain the former in place, a core-former connected to the outer side of said

casting; and means for detachably fastening 25 said tube in place, substantially as described.

14. In combination, a hopper, a removable casting thereunder having a chamber, a feed-inlet communicating with the hopper, and longitudinal and transverse slots in its base; a centering-rib and locking-bar engaging 30 said slots to retain the former in place, a core-former connected to the outer side of said casting; and means for detachably fastening said tube in place, with a series of reciprocating pitmen, plungers on the ends of said pitmen operating in said chamber and together conforming to the contour thereof; and means for operating said plungers in succession, substantially as described. 40

In testimony that we claim the foregoing as our own we affix our signatures in presence of two witnesses.

HARRY L. BELL.

CHARLES C. SWEITZER.
